ALBERT D. JUDD, OF NEW HAVEN, CONNECTICUT.

Design No. 4,630, dated February 7, 1871.

DESIGN FOR A MATCH-SAFE.

The Schedule referred to in these Letters Patent and making part of the same.

To all whom it may concern:

Be it known that I, ALBERT D. JUDD, of New Haven, in the county of New Haven and State of Connecticut, have invented a new Design for Match-Safe; and I do hereby declare the following, when taken in connection with the accompanying drawing and the letters of reference marked thereon, to be a full, clear, and exact description of the same, and which said drawing constitutes part of this specification, and represents a perspective view.

This invention relates to a design for match-safe or holder, and consists in the peculiar configuration and ornamentation, as fully shown in the accompanying drawing.

The box or holder A has a panel-front, over which is looped a wreath of fruit and leaves. Above the box the back extends upward with an arched panel or opening, and bordered by a raised edge with a wreath running up to a central hole on the top, all as fully shown in the accompanying illustration.

I claim as my invention—

The design for match-safe, as herein described and shown.

ALBERT D. JUDD.
